UNITED STATES PATENT OFFICE.

JAMES G. HARDIE, OF CANTON, NEW YORK.

SHEET-FEEDING MACHINE.

1,112,791.

Specification of Letters Patent.

Patented Oct. 6, 1914.

Application filed March 1, 1909. Serial No. 480,810.

To all whom it may concern:

Be it known that I, JAMES G. HARDIE, a citizen of the United States, and a resident of Canton, in the county of St. Lawrence 5 and State of New York, have invented certain new and useful Improvements in Sheet-Feeding Machines, of which the following is a specification.

My present invention relates to improvements in sheet-feeding machines of the sheet-combing type in which the stack of sheets is acted upon by feed-combing devices which comb or feather out the top sheets of the stack to gradually separate the successive sheets near the top, so that they may be drawn from the stack periodically and fed to any machine arranged to operate upon the individual sheets.

My present invention relates to improved features of construction particularly as follows: 1. Means for retarding the sheets in the stack. 2. Means for tilting the comb-arbor. 3. Means to keep the top of the stack of sheets at a uniform height. 4. Means to transfer each sheet from the feeding machine proper to the machine which will operate upon the sheets. 5. Means to place each sheet against stops in the machine that will act upon the sheet.

In order that my invention may be fully understood, I will first describe the same with reference to the accompanying drawings, and afterward more particularly point out the novelty of each feature.

In the accompanying drawings similar figures refer to similar parts.

Figure 1 is the side elevation of what is termed the right side, showing the rear of a cylinder-printing press, from which the power is understood to be received. An end view of the elevator is shown with a stack of papers thereon. Also a side view of the mechanism that carries the sheet from the feeder to the printing press. Fig. 2 illustrates the left side of the feeder with the transfer mechanism elevated from the printing press table. Fig. 3 is a plan view. Fig. 4 is a sectional view of a portion of the main frame of the feeder and the transfer mechanism between the feeder and the printing press. Fig. 5 is a modified form of a portion of the main frame of the feeder and the transfer mechanism. Fig. 6 is a view of the gearing mechanism which rotates the combing devices. Fig. 7 is a rear sectional

view, showing a portion of the side-frame of the combing devices and the means which operate them. Fig. 8 is an end view of the combing-arbor and its bearing with the connections between it and the cam which operates it. Fig. 9 is a sectional view of the tape-trucks and the feed-trucks in the delivery mechanism. Fig. 10 is an end view of the means for regulating the height of the stack of sheets. Fig. 11 is a front view 65 of the mechanism for regulating the height of the stack of sheets. Fig. 12 is a side view of the means for placing the sheets against the stops. Fig. 13 is an end view of the means for placing the sheets against the 70 stops.

Manner of operation.—The sheets to be fed are placed in a stack on the elevator 3, Figs. 1, 2, the top sheet of which contacts the segment 109, Fig. 10. The operator 75 stands upon the platform 110, Fig. 1, and by raising the lever 113 will close the switch 120, thus applying the motive power, which is transmitted through the arbors 5 and 7 (and other mechanism explained later on), 80 that rotate the combs which start the top sheet into the bite between the upper and lower set of delivery tapes 48 and 53. The sheet is then carried against the stop 59, Fig. 4, the stop is then oscillated downward and 85 allows it to pass on between the feed-trucks, 57 and 58, Fig. 9, the front edge passing under the drop-roll 67, and over the advancing-roll 86, which carries the sheet near to the stops on the machine to which it is being delivered. The reciprocating-frame 81, Fig. 3, then pushes the sheet forward against 90 the stops.

Description in detail.

95

Starting and stopping mechanism.—In Fig. 1 is shown the means by which the motive power is applied, and also the same means is used to throw off the power and throw on the braking mechanism at the same 100 time. This means consists of the lever 113 pivoted to the frame 114, with a suitable link between the lever 113 and the power connecting mechanism 120, which in the illustration represents an electric-current 105 switch. Thus by raising the lever 113 the switch 120 is closed, but by pulling downward the lever 113 the switch is opened and through the connection 115 the brake 116 is applied to the fly-wheel 117. The object of 110

this mechanism is that the operator may quickly throw off the motive power and throw on the brake mechanism with the same operation.

5 *Retarding shoe.*—It is desirable to have means to retard the rear of the top sheets of the stack and also that this means may be so regulated and adjusted to adapt itself to the proper retarding of various kinds of 10 paper, so that the combing devices will advance only the top sheet without unduly advancing the succeeding sheets. Also the form of means must be such that it can be quickly set for sheets of various sizes. This 15 device is shown in Figs. 1, 2 and 3 in the form of an arm having several joints and terminated in a flat shoe. 99 is the said arm rigidly attached the frame tie-rod 106 and 20 100 and 101 are links attached to the arm 99. 102 is a link pivotally attached to 101 and the shoe 103. 104 is a rod suitably fixed to the shoe 103, and 105 is an adjustable weight upon the rod 104. Thus by the links 25 100 and 101 the shoe can be moved forward as may be necessary according to the width of the stack it rests upon. The link 102 being pivotally attached admits of the shoe adjusting itself to any variation of the top 30 surface of the stack. The weight 105 will regulate the friction between the shoe and the stack of sheets combed. If desired the 35 under side of the shoe may be covered with any flexible material.

35 *The elevator.*—The elevator consists of a suitable framework having a covering and bearings on each end to take vertical-screws which are suitably journaled in the framework, and which are operated by the bevel-gears 21 which operatively connect the 40 screws with the ratchet-arbor 20. The ratchet-arbor is rotated by the ratchet 19, the pawl-arm 22, the pawl 13, the link 11, which is pivotally attached to the bevel-gear 8. Thus as the gear 8 rotates the elevator is 45 intermittently raised, and whenever desired it is lowered by the hand-wheel 127.

50 *The combing device.*—In a sheet-feeding machine in which the stack of papers is carried upward on an intermittently-movable elevator and where the combing device rotates and at the same time is intermittently raised and lowered to contact the top sheet of the stack, and because the top surface of the stack of sheets is usually uneven it, 55 therefore, is desirable to have means by which the combing devices may be, at any time, so set that they will create on the top sheet the same amount of friction at whatever point they contact, and also that this 60 amount of friction may be increased or decreased at the will of the operator as the surface of the paper may require. These devices are shown in Figs. 4, 5, 6, 7 and 8. In Fig. 7 are shown sectional views of the 65 frame 1 and 2, which constitutes the bear-

ings for the main arbor 9, which is continuously rotated while the machine is in operation. On arbor 9 are rigidly mounted the cams 32. Riding upon these cams are the trucks 34, which are pivotally attached to the connecting links 33. Thus in each rotation of the arbor 9 the links 33 are raised and lowered, and the shape of the cams 32 will determine the time at which the links 33 may remain at their lowest point. In 70 one of the links 33 is pivotally located one of the comb-arbor bearings 92 which is pivoted in the link 33, on the stud 91 while in the other link 33 is placed the other bearing of the comb-arbor 35, which has a vertical movement as shown in Fig. 8. The object of this vertical movement is that at any time the operator may raise or lower one end of the arbor 35 so that the combing devices 80 36 will each contact the top sheet with the same amount of friction. In Fig. 8, 35 is the comb-arbor, 37 is the adjustable bearing, 38 is a spring to hold the bearing downward, while the screw 39 when rotated by the gears 40 will raise or lower the bearing 90 95 37.

42 is an arbor journaled in the bearing 41 on the link 33, and in Fig. 2 on the arbor 42 is shown a hand-wheel 90 by which the operator at any time can adjust the combing 95 devices.

In Fig. 7 and Fig. 6 are shown the gearing mechanism that rotates the arbor 35. In Fig. 6, 29 is a power-driven arbor journaled in the frame carrying a pinion 25, 100 which engages the spur-gear 10 on the arbor 9. Thus in the operation of the machine the gear 43 on arbor 29 is continuously rotated and engages the intermediate 44, which in turn engages the gear 46 upon the comb-arbor 35. The arbors 35 and 29 are kept in alinement by the links 45. Thus in the operation of the machine the combing devices, 36, upon the arbor 35, are continuously rotated by the train of gears 46, 44 and 43, 105 43 being rigid upon the arbor 29 and the pinion 25 upon arbor 29 is engaged with the power-driven gear 10 upon the main arbor 9, and the cams 32 being rigid upon the main arbor 9 at each revolution raise and 115 lower the links 33, carrying with them the links 45.

120 It is understood that the gears which rotate the comb arbor will be set sufficiently far apart that the slight change of the opposite end of the comb-arbor, in making adjustments, will not bind the gears, but will allow them to work freely, as the adjustment of the arbor will be very slight and will throw the gears only a little out of 125 alinement.

125 *The pile regulator.*—In a sheet-feeding machine of the design in which there is an elevator carrying upward a stack of sheets until they contact combing devices which 130

have a fixed and determined point in their descent, it is necessary to have means that will stop the upward movement of the elevator when the top of the stack of sheets 5 has reached a certain height and to so operate the elevator-raising mechanism as to keep the height of the stack of sheets substantially at that height. To accomplish this I use the devices shown in Figs. 10 and 11 in connection with the pawl and ratchet shown in Fig. 1. In Fig. 10, 106 is the stationary-frame tie-bolt; to which the arm 107 is rigidly attached, and pivoted to that arm is the bell-crank 108. Journaled in its short 15 arm is the arbor 16, on which is located the segment 109.

121 is an adjusting-screw to raise and lower the segment. The arbor 16 passes through the frame 1. On the outer end is 20 the finger 15.

In Fig. 1, 14 is a pawl-shoe pivoted to the frame 1, and is of about the same curvature as the ratchet 19. The arm 22 is pivotally hung on the ratchet-arbor 20, and 25 carries in its lower end, and pivoted to it a pawl, pivoted between its ends, one end of which is shaped to engage the ratchet, the other end to ride upon the pawl-shoe. Thus in the operation of the feeder when the 30 stack of sheets has reached a height to contact the bottom of the segment which is suitably located over the stack of sheets and as the combing devices draw the top sheet forward the friction between the top sheet 35 and the segment will rotate the segment and turn the finger 15 upward, which has the effect of lifting the pawl-shoe 14 upward and that in turn raises one end of the pawl so that the pawl becomes inoperative, and 40 though the pawl-arm 22 continuously reciprocates back and forth, yet the ratchet will remain idle, therefore causing the elevator to stop in its upward movement. The elevator will remain stationary until a sufficient 45 number of sheets have been drawn from below the segment 109 to eliminate the friction between the stack of sheets and the segment, and then the segment will, by gravity, rotate back to its normal position, 50 which will cause the finger 15 to be turned downward, lowering the end of the shoe 14, and as the idle end of the pawl is heavier than the work end, the pawl will then engage the ratchet and again start the elevator 55 in its upward movement. By adjusting the screw 121 the segment-bearing will be raised or lowered vertically, thus setting it in position as may be necessary according to the 60 smoothness of the surface of the sheets. By raising or lowering the segment 109 the friction between the combing devices and the stack of sheets can be increased or decreased to suit the necessary pull of the 65 combing devices on the different grades and smoothness of the surface of the sheets.

The device shown in Figs. 10 and 11 is preferably located about the center of the machine in each direction.

18 is a handle pivoted to the frame 1 by which the pawl-shoe can be placed in the 70 position that the pawl will be held so as to be inoperative.

The transfer.—In carrying a sheet from the feeder proper to the machine on which it will be operated it is essential that the sheet shall be carried positively and accurately. In this invention I use a transfer and a delivery table which, taken together, constitute this means. In Fig. 4 is illustrated a sectional view of this mechanism. In 80 Fig. 3 is a plan view in which 47 and 47 held together by the tie-bolts 125 and 126 constitute the transfer-frame, which is pivotally mounted upon the main feed-roll 30. To this framework is pivotally attached the 85 table 64. In Fig. 4, 30 is the main feed-roll, around which pass tapes 31, which carry the sheet from the stack to the main feed-roll 30. On the main feed-roll 30 is the gear 28, in engagement with the power-driven 90 gear 10, through the intermediate gears 25, 26 and 27. In the framework 47 is journaled the arbor 50, on which is rigidly mounted tape-carrying trucks 49, as shown in Fig. 9, and around these trucks pass 95 tapes 48. Also journaled in frame 47 are the arbors 51 and 55. Upon the arbor 55 are loosely mounted tape-carrying trucks 54, and upon arbor 51 are tape-carrying trucks 52 and around these pass the tapes 100 53. Also journaled in frame 47 are the arbors 51 and 55. Upon the arbor 55 are loosely mounted tape-carrying trucks 54, and upon arbor 51 are tape-carrying trucks 52 and around these pass the tapes 105 53. Also on arbor 51 is the sheet-feed-truck 56, which contacts the main feed-roll 30 and is rotated in unison by friction therewith. As shown in Fig. 9, there is mounted upon arbors 50 and 55 the delivery-sheet-trucks 110 57 and 58. It will be observed that the feed-roll 30 and feed-truck 56 are in frictional contact and that delivery-trucks 57 and 58 are in frictional contact. This is so that roll 30 and truck 56 will take hold of 115 the sheet positively, while the trucks 57 and 58 will deliver the sheets positively. It will be observed that the main feed-roll 30 and the tape-truck 52 do not contact, and that the tape-trucks 49 and 54 do not contact. The object of this is that the tapes 48 and 120 53 are held apart, excepting as the top portion of the tape is allowed to sag at the middle, so that when the sheet strikes the stop 59 the friction between the tapes will not roll the front edge of the sheet, but will allow the sheet to lie loosely upon the tapes 48 and thus become perfectly squared to the stop 59. It is understood that the largest sheet will be less than the distance from the 125 stop 59 to the bite of the rolls 30 and 56. The diameter of the tape-truck 52 being less than the diameter of the feed-truck 56, the tapes 53 will not travel as fast as the tapes 48; therefore it is necessary that the 130

tape-trucks 54 shall be loosely mounted on the arbor 55, because the arbor 55 is rotated by the delivery-trucks 57 and 58, and as the arbor 50 is rotated by the tapes 48, 5 traveling at the same surface speed as the roller 30, it follows that the tape-truck 54 will have to move upon the arbor 55. It is desirable that the tapes 53 should travel a little slower than the tapes 48 so as to have 10 the tendency, by slightly sagging, to retard the incoming sheet so that it will not strike the stop 59 hard enough to roll its front edge. Upon the arbor 60 is rigidly attached the arm 61, which is connected with the bell-crank 63 by the connecting-rod 62. The short end of the bell-crank 63 rides upon a cam not shown upon the main arbor 9, the cam operating the crank in one direction, while the spring 12 pulls the bell- 15 crank 63 in the opposite direction. This has the effect of intermittently raising and lowering the stop 59. Thus, in the operation of the transfer the sheet is carried from the combing devices 36 to the main feed-roll 20 25 30 on the short tapes 31 and the front edge of the sheet is caught in the bite of the roll 30 and feed-truck 56 before the combing devices are lifted off of it, thus making a positive movement from the stack of the sheets 30 to the bite of the feed-roll. The sheet is then carried on the tapes 48 and held upon them by tapes 53 until the front edge of the sheet reaches the stop 59, which squares the sheet to the line of travel. The stop 59 is 35 then lowered and the tapes again start the sheet and deliver it into the bite of the delivery-trucks 57 and 58. These trucks advance the sheet until the front edge of the sheet has passed between the truck 86 on the 40 advancing-arbor 124 and the truck 87 on the drop-roll 67.

The distance between the truck 86 and the delivery-trucks 57 and 58 being less than the width of the smallest sheet, therefore the 45 front edge of any sized sheet to be fed will always reach the truck 86 before it leaves the delivery-trucks 57 and 58. The drop-roll 67 is operated by an arm rigid to it, 73, and connected with a bell-crank 75 by the 50 connecting-rod 74. The bell-crank 75 contacts a cam on the main arbor 9, not shown, and is held in contact with the cam by the pull-spring 76. The drop-roll 67 is so arranged that it will contact the truck 86 sufficiently to forward the sheet until the front 55 edge of the sheet nearly reaches the guide-stop against which the sheet is intended to be placed. The drop-roll 67 is then raised so that the sheet will practically come to a 60 stop, but will then be pushed to the stops by devices described later on. Suitably pivoted to the arbor 65 and operated by the drop-roll 67 are devices 88 to retard the sheet and overcome its momentum. These devices 88 65 rest upon the table 64 and pass above the ar-

bor 67 and are so shaped that the arbor 67 rises part way before it contacts the retarding devices 88 and then lifts the retarding devices off of the sheet. The sheet then will be lying loosely upon the delivery-table, not 70 quite up to the stops against which it is to be fed, but it will have been practically brought to rest by the action of the retarding devices lying upon it before they were raised off of the sheet by the upward movement of 75 the drop-feed-roll.

It will be observed that owing to the shape of the retarding devices that the drop-roll will be raised a portion of its movement before it lifts the retarding devices off of the 80 sheet. The object of so shaping the retarding devices is that the drop-roll will be raised off of the sheet and so cease its advancing effect upon the sheet while the retarding devices still remain on the sheet to 85 overcome the momentum of the sheet, the object of which is that the sheet may not be thrown with too great force against the stops by its momentum.

In Fig. 5 is shown a modification of the 90 transfer mechanism between the feeder proper and the machine being fed. The modification consists of using two additional arbors, journaled in the framework, which are pivotally attached to the main feed-roll. 95 On these additional arbors are mounted the tape-trucks, while the feed-trucks remain as in Fig. 4. Means will be used, though not shown, by which these tapes will be driven.

Sheet-placer.—In Fig. 3 is shown a plan 100 view of a reciprocating member, the function of which is to move the sheet forward from the place where it was left by the retarding devices, up to and against the stops or guides against which the sheet is intended 105 to be placed. The object of this means is that the sheet may be moved carefully forward and pushed only to the guides, so that the front edge of the sheet will touch the guides, but not be pressed against the guides. 110 This means consists of the bar 81, either lying upon the machine or placed in slots in the framework 47, which is pivotally attached to the main feed-roll.

72 is an arbor journaled in the frame, and 115 on one end it carries the gear 78 which is in engagement with the power-driven gear 28. On the opposite end of the arbor 72 is the crank 71. Pivots attached to crank 71 is the connecting-arm 80, which is pivotally attached to the bar 81. Also to the gear 78 is pivoted the connecting-arm 79, which is also pivotally attached to the bar 81. Suitably attached to the bar 81 are the forwardly-pointing arms 82, which move in the grooves 120 85, which are cut in the delivery table 64. On the arms 82 are the stops 83, which are held in place by frictional contact. The stops 83 are so shaped that the rear end is below the top surface of the table 64, while 130

the forward end of the stop rises above the table so as to contact the rear edge of the sheet and push it forward. 84 is a shoe on the bottom side of 82 which carries the arm 82 so that the bottom of 83 will not contact the bottom of the groove. Fig. 12 is a side view of the arm 82 with the shoe 84 and the adjustable-stop 83. Fig. 13 is an end view of the stop 83 and a cross-section view of the arm 82. In the operation of this mechanism it will be observed that the bar 81 is reciprocated by a crank movement, and regardless of the size of the sheets being fed it always has the same stroke, but the width of the sheets being fed is cared for by moving the stop 83 so that the distance, when the bar 81 is at its extreme forward point, between 83 and the stop to which the sheet is to be fed, will be equal to the width of the sheet. Thus at each reciprocation of the bar 81 it moves backward while the incoming sheet passes over the stops 83 and when the bar 81 is at its extreme return stroke the stops 83 will then be in rear of the sheet, because the drop-roll is so timed that it will deliver any width of sheet so that the rear of that sheet will be in front of the stops 83, and so that each sheet will be accurately pushed against the stops on the machine being fed. It will be understood that the distance between the truck 86 and the delivery-rolls 50 and 55 is less than the smallest sheet fed, while the distance between the rolls 50 and 55 and the stops of the machine being fed is greater than the width of the largest sheet fed, and as the drop-roll and truck 86 are so adjusted and operated that they will, regardless of the width of the sheet, move the front edge of the sheet the same distance in front of the 40 advance-roll 124, thus regardless of the width of the sheet the rear edge of the sheet will always be moved out from the rolls 50 and 55, placing it in front of the stops 83 when they are at their extreme return stroke. 45 129 is a belt by which the drop-roll 124 is rotated, the power being gotten from the arbor 50.

69 is an arm rigid upon the arbor 70, and carries a truck which contacts the cam 68 upon the arbor 9.

77 is a pull spring that holds the truck upon the cam 68.

90 is a hand wheel by which the comb arbor is raised and lowered.

55 Claims:

1. In a sheet feeding machine having a suitable framework, the combination therewith of a power operated elevator, a power rotated main arbor, a power rotated comb arbor, with suitable sheet combing devices thereon, suitable connections between the main arbor and the comb arbor, one bearing of the comb arbor being pivotedly attached to said connections, and the other bearing of the comb arbor being

slidably mounted in one of the aforesaid connections, means to press downwardly the slideable comb arbor bearing, means adapted to raise the slideably mounted bearing.

2. In a sheet feeding machine having a suitable framework, the combination therewith of a power operated elevator, a power rotated main arbor, a power rotated comb arbor with suitable combing devices thereon, suitable connections between the main arbor and the comb arbor, one bearing of the comb arbor being pivotedly attached to said connections, and the other bearing of the comb arbor being slidably mounted in one of the aforesaid connections, a spring adapted to press downwardly the slideable comb arbor bearing, a screw adapted to raise the slideable comb arbor bearing, means adapted to manually rotate said screw.

3. In a sheet feeding machine having a suitable framework, the combination therewith of an elevator suitably placed in said framework and adapted to support a stack of sheets with means to advance the top sheet of said stack, a power operated pawl and ratchet in operative connection with said elevator, a depending arm attached to said framework, a member adjustably pivoted to said depending arm, a shaft journaled in said adjustable member and in operative connection with said pawl and ratchet, a quadrant rigid upon said shaft and in frictional contact with said top sheet of stack.

4. In a sheet feeding machine having a suitable framework, the combination therewith of an elevator and suitably placed in said framework and adapted to support a stack of sheets with means to advance the top sheet of said stack, a power operated pawl and ratchet in operative connection with said elevator, a bell crank pivoted upon said framework with means to adjust it, an arbor journaled in said bell crank and at right angles to the course of travel of said top sheet, suitable connections between said arbor and said pawl and ratchet, a quadrant mounted upon said arbor and in frictional contact with said top sheet.

5. In a sheet feeding machine having a suitable framework, the combination therewith of an elevator suitably placed in said framework and adapted to support a stack of sheets and with means to advance the top sheet of said stack, a power operated pawl and ratchet in operative connection with said elevator, a shoe suitably pivoted and in operative connection with said pawl and ratchet, a depending arm attached to said framework, a member adjustably pivoted to said depending arm, a shaft journaled in said adjustable member and in operative connection with said shoe, a quadrant rigidly mounted upon said shaft and in frictional contact with said stack of sheets.

6. In a sheet feeding machine having a

suitable framework, the combination therewith of an elevator suitably placed in said framework and adapted to support a stack of sheets and with means to advance the top sheet of said stack, a power operated pawl and ratchet in operative connection with said elevator, a shoe suitably pivoted and in operative connection with said pawl and ratchet, a shaft journaled above said stack of sheets and at right angles to the path of travel of the top sheet, said shaft having one vertically adjustable bearing, a quadrant mounted upon said shaft and in frictional contact with said top sheet.

15 7. In a sheet feeding machine having a suitable framework, the combination therewith of a main feed roll, a framework piv-

otedly attached thereto, a feed arbor journaled in said framework having feed trucks rigidly mounted thereon and contacting the main feed roll, tape carrying trucks rigidly mounted upon the feed arbor which do not contact the main feed roll, a main delivery arbor having trucks mounted rigidly thereon, a second delivery arbor journaled in the said frame work having trucks rigid upon it which contact the delivery trucks on the main delivery arbor, tape trucks loosely mounted upon the second delivery arbor, tapes upon the tape trucks.
